PLANE

Ronald David Carter, Leamington Spa, England, assignor
to Stanley Works (Great Britain) Limited, Sheffield,
England

Filed Mar. 6, 1972, Ser. No. 232,347

Claims priority, application Great Britain Sept. 7, 1971

Term of patent 14 years

Int. Cl. D8—03

U.S. Cl. D8—101

FIG. 1.

FIG. 2

FIG. 3.

FIG. 4.

FIG. 5.

FIG. 6.

FIG. 1 is a side elevational view of a plane showing my new design,

FIG. 2 is a top plan view thereof;

FIG. 3 is a bottom plan view thereof;

FIG. 4 is a rear elevational view thereof;

FIG. 5 is a front elevational view thereof; and

FIG. 6 is a view similar to FIG. 1 but with the handle element in an alternative position.

I claim:

The ornamental design for a plane, as shown and described.
